UNITED STATES PATENT OFFICE.

VICTOR ZIMMERMANN, OF VIENNA, AUSTRIA.

LOCK.

1,355,725.

Specification of Letters Patent.

Patented Oct. 12, 1920.

Application filed November 18, 1919. Serial No. 339,004.

To all whom it may concern:

Be it known that I, VICTOR ZIMMERMANN, a citizen of the Republic of Czechoslovakia, and a resident of Vienna, in the Republic 5 of Austria, have invented a new and useful Improvement in Locks, of which the following is a full, clear, and exact description.

The present invention relates in general to locks and has particular reference to that 10 class of locks such as are used on doors or the like, and which employ both a latch and a bolt.

The primary object of the invention is to provide a lock in which the latch is mounted 15 normally free to be manipulated for opening and closing the door under ordinary conditions, and also to provide a key controlled bolt that is normally maintained inactive, but which may be released by the 20 key and actuated by a manipulating means to active position locking the door, and which will be maintained in this position so long as the key is removed from controlling relation thereto, but which may be released 25 from active position by the key and manipulated to inactive position when unlocking the door.

While the functioning of the lock just described is somewhat similar to heretofore 30 known locks of this character it would be in order to state that the invention in its preferred form contemplates providing a single means for actuating the latch and the bolt. By this arrangement and with the key in releasing relation relative to the bolt a single 35 manipulating means turned in one relation such as clockwise, will actuate the latch to inactive position, and when released permit the latch to assume an active position under 40 the influence of a spring, and when the manipulating means is turned anti-clockwise the same will actuate the bolt to active position, and when again turned in a clockwise direction it will actuate the bolt to 45 active position, as well as the latch, whereupon when it is released the latch will assume an active position as stated under the influence of a spring.

This is all accomplished as long as the key 50 is in releasing relation relative to the bolt and its associated parts. When the key is removed from its controlling position the bolt is maintained in active or inactive position as the case may be with the manipulating 55 means only actuating the latch.

The accompanying drawings illustrate the invention and in which—

Fig. 1 is a side elevation of a door lock with the side plate removed illustrating the coöperative relationship of the parts. 60

Fig. 2 is a front view of the face plate showing the relative position of the latch and bolt.

Fig. 3 is a sectional view on the line 3—3 of Fig. 1. 65

Fig. 4 is a view similar to Fig. 1 showing the parts in different position.

Fig. 5 is also a side elevation of the parts in a third position.

Fig. 6 is a sectional view on the line 6—6 70 of Fig. 4.

Fig. 7 is a side view of a modified bolt and latch arrangement.

Fig. 8 is a front view of a part of the face plate showing the bolt as proposed in Fig. 75 7, and

Fig. 9 is a side elevation of a part of the lock illustrating a modification of the latch and bolt actuating means.

Referring to the drawings in detail the 80 latch 1 and the bolt 2 are slidably mounted in a suitable housing 3 which has a removable side piece 4 and a front face 5 having openings therein through which the latch and bolt are adapted to extend (see for instance Figs. 1 and 2.) Under the influence of a coil spring 6 which is mounted on the post 7 its opposite end bearing against the shoulder on the latch, the latch is adapted to be maintained normally active as is customary in latches of this kind. The same is 85 slidably mounted in the housing by means of the post 8 and a shoulder on the opposite side of the rollback 9, thus the end of the latch is practically confined between two 90 confronting shoulders. The post 8 also acts as a stop to limit the outward movement of the latch relative the face plate to which end the end of the latch is provided with a shoulder as at 10, which is adapted to engage the post 8 as clearly shown. The rollback 9 is provided with a bore 11 made to 95 receive the shank of a manipulating device such as a knob or handle, and it is further provided with a vertical extension as at 12 100 which is adapted to overly the latch and provide a shoulder which may engage a stud 13 on the latch adjacent the end thereof, whereupon by turning the rollback by the manipulating means in a clockwise di- 110

rection the shoulder will bear against the stud 13 and retract the latch in the housing the same being returned to normal position under the influence of the coil spring 14 5 which is anchored to the post 15 with its opposite end bearing against the rollback. With this construction it will be readily seen how the latch is actuated.

In so far as concerns the manipulation of 10 the bolt the following construction is to be considered. Pivoted as at 16 is a vertically presented lever 17, the opposite end of which is confined in a recess 18 in the bolt 2. The inner end of the bolt is fixed to a rectangular frame 19 which together with the recess in the bolt confines the end of the lever 17 in the recess mentioned. This frame 19 is slidably mounted between the posts 20 and 21 and adapted to confine a 15 plurality of flat springless tumblers 22 each of which being irregularly slotted and collectively made to receive a post 23 which is fixed to the housing of the lock, and extends through one series of slots in the tumblers. The tumblers are capable of a limited 20 sliding vertical movement in the frame 19 whereupon a key 24 may be inserted in an opening in the one side of the lock housing and engage the tumblers with its end seated 25 in an opening in the opposite side of the housing. The key is provided with a multiplicity of staggered slots or grooves coinciding with the position which the tumblers must assume to release the bolt where- 30 by the tumblers may be so positioned that a space as at 25 may be arranged to permit the post 23 to pass therethrough. So long as the key is removed the space 25 will be closed so far as concerns the passage 35 of the post 23 thus maintaining the post 23 in the space on either side of the space 25; thus preventing any movement of the bolt 2 to or from active or inactive position. As shown in Fig. 1, the post 23 is confined in 40 the space to the left of the space 25 with the bolt thus located in inactive position. By inserting the key in controlling relation relative to the tumblers and positioning the tumblers the space 25 will be arranged to 45 accommodate the passage of the post 23 (see for instance Fig. 4), whereupon by turning the manipulating means for the roll back in an anti-clockwise direction the extension 12 of the rollback will bear against the side of 50 the lever 17 and move the same in a direction toward the face plate 5 and consequently with the end of the lever confined in the recess 18 the same will slide the bolt outwardly from the face plate 5 or in other 55 words to active position, with the post 23 passing through the opening 25 to the space in the tumblers to the right thereof. When the bolt has thus been moved to active position by removing the key the post will be 60 maintained in the space to the right of the

space 25 whereupon the bolt will be lodged in action position. By again inserting the key the tumblers will be positioned whereby the post will be accommodated in the space 25 permitting the bolt to be manipulated to 70 inactive position.

It is of course to be noticed that with the absence of a spring to retract the bolt 2 in the housing 3 some means for manipulating the lever 17 to effect this result is necessary. 75 This can be conveniently accomplished by means of the shoulder 1^A on the latch, 1 so that when the latch is retracted by the manipulating means the shoulder 1^A will bear against the side of the lever and impart a 80 sliding movement to the bolt for receiving the same within the housing.

It will be readily seen that with the exception of the springs 6 and 14 the working parts of the lock particularly the tumblers 85 do not require any sensitive spring structure or the like to properly function which is a decided advantage over heretofore known devices of this general character. Then again the key is not to be turned at 90 all, but merely inserted in the openings made to receive it, and it therefore does not manipulate the bolt to active or inactive position, but merely releases the same so that the latch manipulating means may perform its function. 95

The modification of the bolt and tumbler arrangement shown in Figs. 7 and 8 includes a spring whereby the bolt 2 instead of being made solid as in the other figures is made up of a plurality of superimposed plates which are slidably mounted as in the case of the solid bolt in the housing 3 with the tumbler arrangement provided as an integral part of the bolt. In other words, instead of fixing the frame 19 to the bolt 2 with the tumblers confined in the frame each of the plates producing the bolt are slotted and arranged to provide tumblers which are engaged by the key 24 in a manner as in the other form to position the same so as to permit the posts 23^a which are fixed to the housing 3, to permit the bolt to slide to and from active and inactive position. The bolt opening in the face plate 5 will of course be slightly longer than the bolt so as to accommodate the plates which go to make up the bolt when they are out of horizontal alinement. The bolt will be slotted as at 18 as in the other form to accommodate the end of the lever 17. 110

In the modification shown in Fig. 9 operation of the device is substantially identical with the other forms and the bolt and tumbler arrangement may be either of the 115 forms as described, however the latch, rollback and their associated parts are slightly changed for instance, the latch in this form is slotted as at 26 with a pin 27 received therein, and with the coil spring 28 120 received therein, and with the coil spring 130

bearing against the finger 29 which is pivoted as at 30 with the pivot capable of a sliding movement in the slot 31. The rollback is provided with a downwardly presented tongue 32 which is received in the recess 33 in a sliding arm 34 through the end of which is passed the lever 35 which is pivoted as at 36 and adapted to operate the same as in the case of the lever 17 in the other forms. The sliding arm 34 is provided with a shoulder as at 37 which bears against the pin 38 whereby the rearwardly sliding movement of the lever 35 in the housing is arrested. A suitable coil spring 39 which is anchored as at 40 with its opposite end presented against the arm 34 is employed to maintain the arm in proper functioning position.

Having thus described my invention what I claim as new and desire to secure by Letters Patent is as follows:—

1. In a lock, a latch, means for operating the latch, a locking bolt, means for locking the bolt in position, means for releasing the bolt locking means, and means for operating the bolt from the latch operating means.

2. In a lock, a latch, means for operating the latch, a locking bolt, a plurality of key controlled tumblers for locking the bolt in position, and means for operating the bolt from the latch operating means when the bolt is released by the tumblers.

3. In a lock, a latch, means for operating the latch, a locking bolt, a plurality of sliding tumblers for locking the bolt in position, a key for operating the tumblers to release the bolt, and means for operating the bolt from the latch operating means.

4. In a lock, a latch and a bolt, said latch adapted to normally assume an active position, a rollback adapted to be moved in one direction to slide the latch to inactive position, means associated with said rollback and said bolt adapted to be actuated when the rollback is moved in an opposite direction to slide the bolt to active position, and means coöperating with the means associated with the rollback and the bolt, operable upon the sliding of the latch to inactive position to slide the bolt to inactive position.

5. In a lock, a latch and a bolt, said latch adapted to normally assume an active position, a rollback adapted to be moved in one direction to slide the latch to inactive position, means associated with said rollback and said bolt adapted to be actuated when the rollback is moved in an opposite direction to slide the bolt to active position, and means coöperating with the means associated with the rollback and the bolt operable upon the sliding of the latch to inactive position to slide the bolt to inactive position, and means for maintaining the bolt in an active or an inactive position.

6. In a lock, a latch and a bolt, said latch

adapted to normally assume an active position, a rollback adapted to be moved in one direction to slide the latch to inactive position, means associated with said rollback and said bolt adapted to be actuated when the rollback is moved in an opposite direction to slide the bolt to active position, and means coöperating with the means associated with the rollback and the bolt, operable upon the sliding of the latch to inactive position to slide the bolt to inactive position, a series of tumblers associated with said bolt adapted to coöperate with a key, whereby the bolt may be released in active or inactive position, but adapted to maintain the bolt inoperative when disengaged by the said key.

7. In a lock, a latch and a bolt, said latch adapted to normally assume an active position, a rollback adapted to be moved in one direction to slide the latch to inactive position, means associated with said rollback and said bolt adapted to be actuated when the rollback is moved in an opposite direction, to slide the bolt to active position, and means coöperating with the means associated with the rollback and the bolt, operable upon the sliding of the latch to inactive position to slide the bolt to inactive position, said means associated with the rollback and the bolt comprising a lever pivoted at one end with its opposite end carried by the bolt, said rollback adapted to have a wiping contact with said lever to manipulate the same, to slide the bolt to active position and means on the latch adapted to contact with the lever when the latch is slid to an inactive position to slide the bolt to inactive position.

8. In a lock, a latch and a bolt, said latch adapted to normally assume an active position, a rollback adapted to be moved in one direction to slide the latch to inactive position, means associated with said rollback and said bolt adapted to be actuated with the rollback as moved in an opposite direction to slide the bolt to active position, and means coöperating with the means associated with the rollback and the bolt, operable upon the sliding of the latch to inactive position, to slide the bolt to inactive position, said means associated with the rollback and the bolt comprising a lever pivoted at one end with its opposite end carried by the bolt, said rollback adapted to have a wiping contact with said lever to manipulate the same, to slide the bolt to active position and means on the lever adapted to contact with the lever when the latch is slid to an inactive position to slide the bolt to inactive position.

9. In a lock, a latch and a bolt, said latch adapted to normally assume an active position, a rollback adapted to be moved in one direction to slide the latch to inactive position, means associated with said rollback and the bolt comprising a lever pivoted at one end with its opposite end carried by the bolt, said rollback adapted to have a wiping contact with said lever to manipulate the same, to slide the bolt to active position and means on the lever adapted to contact with the lever when the latch is slid to an inactive position to slide the bolt to inactive position; said bolt having associated therewith a series of tumblers and a key adapted to engage said tumblers, to position the same to permit the sliding of the bolt to and from active and inactive position, said

tumblers adapted to maintain the bolt in any one of said two positions when it is disengaged by the key.

9. In a lock, a sliding latch and a sliding bolt, a rollback adapted to be moved in one direction to slide the latch to inactive position, a spring for returning the latch to active position when released by the rollback, a pivoted lever engaging the bolt, adapted 10 to contact with the rollback when the same is moved in a direction opposite to that to slide the latch, to slide the bolt to active position, a shoulder on the latch adapted to contact with said lever, when the latch is

slid by the rollback, to slide the bolt to inactive position, and a tumbler arrangement associated with the bolt made to receive a key, said tumbler arrangement adapted to maintain the bolt inoperative, and said key adapted to position said tumbler arrangement to render the bolt operable.

10. In a lock as set forth in claim 9 and in which the tumbler arrangement comprises a series of irregularly slotted plates with the key notched to engage and position said 20 slots in releasing relation relative to the bolt.

VICTOR ZIMMERMANN.
